DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 80 cents a sheet.

Defensive Publication applications have not been examined as to the merits of alleged invention. The Patent Office makes no assertion as to the novelty of the disclosed subject matter.

3 Sheets Drawing. 17 Pages Specification

Photographic apparatus, such as a camera, for sensing the condition of and for firing a percussive flash device. The flash device includes a lamp and a striker (7) lodged in an energized position from which it is releasable to fire the lamp. The apparatus includes an actuating member (102) movable from a first position retracted from the flash device, to a second position for sensing and engaging an energized striker in the device, and to a third position for releasing the striker to fire the device. The member is moved from the first position to the second position in response to initial depression of the camera body release. Thereafter, movement from the second position to the third position and back to the first position is effected by translation of a driver from an energized condition to a released condition.
